UNITED STATES PATENT OFFICE.

JOHN VODICKA, OF CHICAGO, ILLINOIS, ASSIGNOR TO CINCH FASTENER CORPORATION, OF CHICAGO, ILLINOIS, A CORPORATION OF ILLINOIS.

CURTAIN FASTENER.

1,425,618.

Specification of Letters Patent. Patented Aug. 15, 1922.

Application filed October 4, 1920. Serial No. 414,438.

To all whom it may concern:

Be it known that I, JOHN VODICKA, a citizen of the United States, residing in Chicago, county of Cook, State of Illinois, have 5 invented certain new and useful Improvements in Curtain Fasteners, of which the following is a specification.

My invention relates to that class of fasteners which are employed for holding the 10 curtains of carriages, motor cars and the like in position, in which a socket is provided on the frame and receives an entering member provided with a catch for removably retaining it within the socket, the entering member being secured to the curtain.

An object of the invention is to provide 15 such a fastener which will dispense with the unsightly and inconvenient projections and cavities commonly found in devices of this character and which may be readily and conveniently operated to secure and release the curtains when desired.

In the accompanying drawing and following 20 specification I have shown and described a preferred form of my invention; it is to be understood, however, that the specific disclosure is for the purpose of exemplification only and that the scope of the invention is defined in the following claims, in 25 which I have endeavored to distinguish it from the prior art so far as known to me without, however, relinquishing or abandoning any portion or feature thereof.

In the drawing Fig. 1 is an axial section 30 through a fastener embodying the preferred form of the invention; Figs. 2 and 3 elevations of details and Figs. 4 and 5 axial sectional views of other details.

In the specific form of the invention disclosed 35 the socket 4 is adapted to be let into the post or frame members *a* of a carriage or car body and the entering member 5 secured to the curtain. The socket member comprises a cup 6 of generally cylindrical shape, the bottom 7 of which is formed with an interior threaded perforation 8 which may receive a screw *b* for anchoring the cup in the bore or hole made to receive it in the framework of the car body. The edge of the cup 45 is outwardly flanged as at 9 to receive an annular rim member 10, the outer edge of which is upset over the flange 9, and the inner periphery of which is inwardly turned at 11 for engagement with the hooks of the 50 entering member as will presently appear.

The socket member 6 contains a circular follower 12 which is pressed outwardly or away from the bottom 7 by a spring 13 intermediate the follower and bottom, and when there is no entering member projecting into 60 the socket the follower plate 12 is pressed by the said spring against the inwardly turned edge of the annular member 10 closing the socket against the entry of dirt or other foreign matter and giving it a neat appearance. 65

The entering member comprises a cylindrical barrel 14 of a size to fit easily within the opening of the annulus 10 and the entering end thereof is inwardly dished as at 15 for increased strength. The other end of 70 the barrel 14 is open and somewhat enlarged as at 16, thus forming an inner shoulder at 17 and an outer shoulder at 18 for purposes which will presently appear. The catches 19, 20 for engaging with the socket member 75 are fulcrumed upon the inner shoulder 17 which is rounded off for this purpose, the catches being provided with rounded re-entrant surfaces 21 for engagement with said shoulder. Said catches at their remote 80 ends are formed with hooks 22, 23 which normally extend beyond the cylindrical wall of the barrel 14 which is slotted at its entering end as at 24 for this purpose. The catches are knuckled or pivoted together by 85 means of a partly circular projection 25 on catch 20 and a similarly shaped notch 26 on catch 19 by reason of which construction the catches are projected and retracted simultaneously. Means for normally maintaining 90 the catches in projected position and for retracting them when desired are provided in a spring 27 and a hollow plunger or finger piece base 28 which latter normally projects beyond the end of the barrel and is reciprocable therein. The outer end of the finger piece or plunger is closed as at 29 and the spring 27 to which reference has been made is located within the plunger and compressed between the end thereof and a hump or 95 bulge 30 formed upon the catch 19. It will thus be seen that the spring normally holds the plunger in outer position and at the same time maintains the catches in projected position. The cylindrical wall of the 100 plunger is provided at diametrically opposite locations with bayonet joint slots 31 through which the respective catches extend, and a shoulder 32 which serves to limit the outward movement of the plunger by engag-

110

ing the edge 33 of a perforation of washer 34 through which the reduced end 35 of the plunger reciprocates. The outer edge of washer 34 is turned over the edge of the 5 flange 36 of the eyelet 37 and the neck 38 of the latter extends under shoulder 18 of the barrel. The edge of the fabric 39 of the curtain is clamped between flange 36 and a washer 40 which is placed over the neck of 10 the eyelet and secured firmly in place by upsetting the edge of the neck thereover.

In assembling the curtain member the catches 19, 20 are placed in position in the barrel 14 with their lower ends projecting 15 through the respective slots therein, the spring 27 placed in position on the hump 30 and the plunger inserted in the barrel over the spring and with the lower ends of the bayonet slots over the respective catches. 20 The plunger is then slipped into the barrel until the shoulders 41 of the slots engage the respective catches and then partly turned to bring the upper legs of the bayonet slots over the catches, this being the normal relative 25 position of these parts as shown in Fig. 1, thus putting the spring 27 under compression. In this position the shoulders 19^a, 20^a of the hook members 19, 20 rest upon the shoulders 35^a of the plunger and thus resist 30 the action of the spring when the latter has forced the hooks to the position shown in Fig. 1. The ring 31^a having been placed in position either before or after the above described assembling operation, the 35 outer washer 34 is slipped over the reduced end of the plunger into contact with the enlarged end of the barrel and the eyelet over the other end of the barrel. The outer edges of said washer and eyelet are then secured 40 together as shown. This completes the assembling of the curtain member and it is then ready to be applied to the curtain by inserting the neck of the eyelet through a 45 purpose, putting the washer 40 over said neck and turning the edge of the neck over the inner edge of the washer, whereby the fabric is clamped between the edges of the washers 34, 40. The assembling of the 50 socket member is too obvious to need description.

The catch members are formed with cam surfaces 43, 44 and when the plunger is depressed by the application of the finger 55 the shoulder 41 of the respective slots ride down the cam surfaces of the catches and force the hook ends of the catches inward. When the plunger is released the spring forces it outward and also forces the catches 60 outward to the normal position shown in Fig. 1. The spring 27 may be made either stronger or weaker in effect than spring 13 and the action of the fastener will differ accordingly. If the spring 27 is made 65 stronger than spring 13 the follower 12 will

act merely as a closure without otherwise effecting the operation of the fastener. With such construction when the curtain member is inserted in the socket the end of the barrel forces the follower down, the 70 rounded edges of the catches engaging the annular member of the socket causing the former to yield inwardly until the hooks clear the inwardly extending flange of the socket 11, when, if the plunger is not under 75 pressure the catches spring out into the position shown in Fig. 1. If the plunger has been under pressure the catches assume the illustrated position as soon as the plunger is released. To release the curtain member from 80 the socket the former is grasped and the plunger depressed to withdraw the catches and the entering member may be withdrawn from the socket. As heretofore stated, if the spring 13 is superior in effect to spring 85 27 the curtain member may be released merely by pressure upon the plunger and without grasping the curtain or the body of the curtain member. As soon as the catches are released by the pressure on the plunger 90 the release of this pressure is first followed by the expansion of the spring 13 which drives the entering member out of the socket, the catches remaining retracted until this has been accomplished. With this construction, 95 therefore, to release the fastener nothing more is necessary than to exert the necessary pressure on the plunger to withdraw the catches.

I claim—

100

1. In a curtain fastener a socket and an entering member having means for retaining it in the socket and a follower in the socket adapted to close the opening therein when the entering member is withdrawn.

105

2. In a curtain fastener and in combination with an entering member a socket having an inwardly extending flange to be engaged by said entering member a follower reciprocable in the socket adapted to engage 110 said flange and a spring pressing the follower toward said flange.

3. In a curtain fastener a socket, a follower within the socket, a spring forcing the follower toward the mouth of the socket, a 115 curtain member having a portion adapted to enter the socket, a catch in the entering member to engage the socket, a spring forcing the catch toward engaging position and a plunger movable relatively to the catch 120 for withdrawing the latter against the pressure of the spring.

4. In a curtain fastener a socket member, a follower therein, a spring forcing the follower toward the opening of a socket, an 125 entering member, a catch on the entering member adapted to engage the socket, a plunger engaging the catch movable relative thereto to withdraw the catch and resilient means for restoring the plunger and catch 130

to normal positions, said spring being effectively inferior to the spring in the socket, whereby the latter operates to expel the curtain member before the catches become operative.

5. In a curtain fastener a socket member, a follower adapted to close the opening in the socket member, a spring normally forcing the follower to closed position, a curtain member having a portion adapted to enter said socket, catches in the entering member adapted to engage the socket and prevent the withdrawal of the entering member, a plunger engaging the catches and adapted when depressed to withdraw the latter from operative position and a spring intermediate the plunger and catches for restoring them to normal position when pressure on the plunger is relieved.
10. 6. In a curtain fastener a socket member, a follower adapted to close the opening in the socket member, a spring normally forcing the follower to closed position, a curtain

member having a portion adapted to enter said socket, catches in the entering member adapted to engage the socket and prevent the withdrawal of the entering member, a plunger engaging the catches and adapted when depressed to withdraw the latter from operative position, a spring for retracting 30 the plunger, the spring in the socket being effectively superior to the spring in the curtain member.

7. In a curtain fastener and in combination with a socket, a curtain member comprising a slotted barrel, a pair of catches mounted to swing in the barrel and to project through the slotted portion thereof into engagement with the socket, said catches being pivoted together, a hollow plunger 40 mounted to reciprocate in the barrel and to engage said catches to withdraw the same into the barrel and a spring intermediate said plunger and catches impelling them to normal position.

JOHN VODICKA.
